US00D632282S

(12) United States Design Patent
Kitayama

(10) Patent No.: US D632,282 S
(45) Date of Patent: * Feb. 8, 2011

(54) EARPHONE

(75) Inventor: Sohei Kitayama, Tokyo (JP)

(73) Assignee: Sony Corporation, Tokyo (JP)

() Term: 14 Years

(21) Appl. No.: 29/347,563

(22) Filed: Mar. 4, 2010

(30) Foreign Application Priority Data

Oct. 28, 2009 (JP) D2009-25260

(51) LOC (9) Cl. 14-01

(52) U.S. Cl. D14/223

(58) Field of Classification Search D14/205, D14/206, 223, 249; 379/430, 420.04; 381/380, 381/381; 181/129, 130, 135; D24/174; 128/864, 128/865; 455/90.3, 575.1, 575.2

See application file for complete search history.
